UNITED STATES PATENT OFFICE

152,297

DESIGN FOR A BADGE OR THE LIKE

Jesse E. Smith, Greenbelt, Md.

Application January 21, 1947, Serial No. 136,269

Term of patent 14 years

(Cl. D29—2)

To all whom it may concern:

Be it known that I, Jesse E. Smith, a citizen of the United States, residing at Greenbelt, Maryland, have invented a new, original, and ornamental Design for Badge or the like, of which the following is a specification, reference being had to the accompanying drawing, forming part thereof.

Figure 1 is a plan view of my ornamental design for a badge or the like, and

I claim:

The ornamental design for a badge or the like, substantially as shown.

JESSE E. SMITH.
